[57] CLAIM

The ornamental design for a cup with closure spout, as shown and described.

DESCRIPTION

FIG. 1 is a top, front, and left side perspective view of a cup with closure spout showing my new design; FIG. 2 is a front elevational view, the rear elevational view being a mirror image thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a right side elevational view with spout in closed position; and,

FIG. 8 is a top plan view with spout in closed position.

FIG. 1

FIG. 2

FIG. 3

FIG. 4

FIG. 5

FIG. 6

FIG. 7

FIG. 8
